UNITED STATES PATENT OFFICE.

FRED E. JONES, OF BROCKTON, MASSACHUSETTS, ASSIGNOR OF ONE-HALF TO
DR. HENRY J. LUPIEN, OF BROCKTON, MASSACHUSETTS.

WELT-INSOLE.

1,279,705.

Specification of Letters Patent. Patented Sept. 24, 1918.

Application filed March 30, 1917. Serial No. 158,556.

To all whom it may concern:

Be it known that I, Fred E. Jones, a citizen of the United States, and resident of Brockton, in the county of Plymouth and State of Massachusetts, have invented an Improvement in Welt-Insoles, of which the following description, in connection with the accompanying drawings, is a specification, like letters on the drawings representing like parts.

My present invention is an improved construction for boots and shoes, and more particularly relates to the manufacture of welt boots and shoes.

In the manufacture of the usual types of welt boots and shoes as now practised, it is necessary to prepare an insole with a channel and sewing rib thereon, then attach the upper and welt to the insole, then to fill the space within the area of the sewing rib with some material, usually ground cork and cement, applied hot, then to level off this "filler" and coat the welt and sometimes the filler surface with cement or other adhesive and then to apply the outsole. These operations are rendered necessary by the use of any of the commercial types of innersole at present available.

The object of my invention is to simplify the manufacture of welt boots and shoes, to eliminate the several steps above mentioned, save cost and work of a filling material, and to provide an inner sole which itself constitutes all the filling necessary. A further important feature consists in the provision of attaching means between the insole and the outsole, eliminating the necessity for coating the innersole or filler with adhesive or the like. A still further important feature in my present invention consists in the utilization of a novel material for the innersole and in the process of making the same. I have discovered that the use of rubberlike material, preferably reinforced with a suitable fibrous mixture of textile material, either in layers, strips or simply as a mass contained within the rubberlike material, will enable a stitch-holding rib to be formed, and therefore produce a practically rubberlike welt insole capable of holding the in-seam stitches.

I am aware that rubber and rubberlike soles have been used for outsoles, heels, and the like, but the peculiar and special re-

quirements for a welt insole, have heretofore been thought insurmountable in using rubber. By my invention I may employ sheets or layers of rubber or reinforced rubberlike material intermixed with textile reinforcements such as canvas layers and mold a sewing rib directly around the contour of the insole with the reinforcements molded therein, whereby a reinforced stitch retaining sewing rib is produced. I consider this feature of great importance and wish to claim the same broadly.

In carrying out my said invention I first prepare a sheet of rubberlike material with the fibrous reinforcements where desired therein, or with the textile layers incorporated therewith; and I then die out from the sheet a proper insole blank of suitable size and contour. Then I subject the same to heated molds and apply pressure sufficient to form around the edge of the shank and forepart the channel and sewing rib, as well as the feather of the insole. This molding pressure further acts to strengthen, solidify and toughen the insole material at the sewing rib, giving a strong "between-substance" for the in-seam stitching. If desired, also, I may apply to the molded insole a series of tacks extending and projecting outwardly from the "filler portion" of the insole toward the outsole, which tacks will receive and hold the outsole without any additional attaching means when the latter is applied thereto, during the subsequent steps in the manufacture of my improved shoe. It will be appreciated that this filler portion of my novel insole may be built up of a plurality of layers or of pieces, should a more economical construction be desired. Preferably, however, I make my rubberlike insole and the filler and rib portion therefrom integral, and of one homogeneous mass. This gives me the benefit of a greater wearing surface throughout the combined thickness of the insole and outsole, greater ease for the foot and practically makes a solid shoe.

Referring to the drawings illustrating a preferred embodiment of my invention.

Figure 1 is a plan view of my improved insoles showing the combined filler and insole construction.

Fig. 2 is a side view of the insole;

Fig. 3 is a cross sectional view across the filler and sewing rib portion illustrating the

simple type of molded rubber or rubberlike insole;

Fig. 4 is a similar cross sectional view illustrating the reinforced type of rubberlike insole, and with the outsole attaching tacks fitted therein;

Fig. 5 is a cross sectional view of my insole with the filler portion made up of a plurality of layers and sections.

10 Fig. 6 is a cross sectional view illustrating a special type of channel, rib and feather, which I find suitable for molding, together with a layer of leather or canvas to protect the feet of the wearer from direct 15 contact with the rubber of the insole.

Fig. 7 is a cross sectional view of my improved boot or shoe with the insole constituting the combined welt insole and filler.

It will be appreciated that several features of my invention are broadly new and 20 I wish to claim the same irrespective of the combinations illustrated in the attached drawings. My welt insole comprising a rubberlike material, containing therein fibrous 25 reinforcements as an integral part of the rubberlike material, thus internally reinforcing the rubber so as to give such retaining capacity, is believed to be new, also I believe that my welt insole having an integral 30 filler member, is new.

Referring to the drawings, Fig. 1 is a plan view of my insole, wherein the main portion 1 is of any suitable style or contour and on which the sewing rib 2 is formed around 35 the margin, leaving the feather 3 and the channel 4. The central part of the shank and forepart of the insole 5 is of suitable depth and extent to constitute a filler and to take the place of the usual cement and 40 ground cork filling material, which has to be applied between the insole and outsole in welt shoes, to fill in the space inside the sewing rib and welt. Preferably I form the filler 5 the same extent as the height of 45 the rib 2. Thus, by taking a sheet of material of equal thickness throughout, and molding the edge portion into the feather 3, rib 2 and channel 4, I form the insole complete with the filler portion integral there- 50 with. This operation of molding an insole eliminates all the operations now required in the manufacture of leather or leather and canvas insoles, which consists in splitting the leather edge, cutting channels, turning 55 up the lip or rib, and then usually reinforcing the entire ribbed surface by canvas to make a "Gem" insole. The great cost of leather thick enough to work into an insole, either when gemmed or not, is a very ma- 60 terial expense in shoe manufacture, as well as the numerous labor operations incident thereto. My molded insole eliminates all these, and further eliminates the subsequent insole trimming operation, the filling, cutting operations, and necessary extra han- 65

dlings incident to prior methods in the manufacture of welt shoes.

As shown in Fig. 4, the insole of rubber or rubberlike material comprises the mass 10 with textile reinforcing layers 11 and 12 70 therein, which are capable of molding into the feather 13, rib 14 and channel 15, similar to the insole of Fig. 3. These textile reinforcements will be molded up sufficiently into the rib 14 and feather 13 to greatly 75 stiffen and strengthen them, particularly to render the between-substances at the base of the rib 14 capable of holding the inseam stitching. I have illustrated in Figs. 4 and 5 the outsole attaching devices consisting in 80 a set or series of tacks 16 and 17, which may be five or six in number and at suitable places throughout the area of the insole.

In Fig. 5, I have shown an insole 20 with the sewing rib 21 and feather 22 thereon 85 and having the filler portion built up of a plurality of layers 24, 25, and 26, 25 and 26 being shown as scraps or pieces which could well be utilized for this purpose and cemented or otherwise united with the body 90 of the insole 20. In Fig. 6 I have shown a type of insole 30, with a special form of sewing rib 31, feather 32 and channel 33 therein, the latter giving particular clearance for the curved sewing needle of the inseam stitching 95 machines. In this form of the insole, the central filler portion 34 may be formed integrally with the insole 30 or built up of layers, as desired. I have shown the layer 35, which may be in the nature of a sock 100 lining, or as a further reinforcing applied to the insole to protect the foot of the wearer from contact with the rubberlike material of the insole, and thus to prevent "drawing" or such objections to a rubber lining inside 105 the shoe.

In Fig. 7 is shown a cross section of my improved boot or shoe, wherein the insole 1 is united to the welt 40 and upper 41 by the inseam stitching 42 in the usual manner. 110 The canvas or textile reinforcing or sock lining 43 is shown in proper position. The outsole 44, either of leather, rubber or fiber, is shown attached to the welt 40 by the usual outsole stitching 45, thus completing the 115 shoe and giving a substantial solid bearing from the lining 43 to the outer surface of the outsole.

My improved shoe as thus formed with any of the various modified forms of insole, whether said insole is of rubberlike material or of other material having the filler 5 integral therewith, gives a completed shoe with a combined innersole and outsole giving a solid foot bearing mass of greater 125 thickness than has heretofore been feasible, because the loose filler material is eliminated, thus insuring greater comfort and wearability in a shoe, as well as affording an economical, serviceable and strong con- 130

struction which is also capable of being made by the ordinary standard types of shoe machinery now in use and without new methods of shoe manufacture. Also my 5 rubber insole may be gemmed if desired.

I have employed the word "rubberlike" in the usual meaning in which this term is employed in the trade, meaning to include rubber, rubber mixtures and rubber substitutes, as well as both natural and synthetic 10 rubbers, and being covered by the usual term of "rubberlike."

My invention is further described and defined in the form of claims as follows:

15 1. A welt innersole of rubber and textile

material with a sewing rib and a central filler portion integral therewith.

2. A welt innersole comprising a rubber-like material, reinforcing layers within said material, and a sewing rib formed around 20 the margin of the sole, said reinforcing layers extending into the base of said sewing rib to constitute stitch retaining means.

In testimony whereof, I have signed my name to this specification, in the presence 25 of two subscribing witnesses.

FRED E. JONES.
